UNITED STATES PATENT OFFICE.

HENRY A. CHRISTY, OF CHICAGO, ILLINOIS, ASSIGNOR TO AMERICAN CAR ROOF COMPANY, OF CHICAGO, ILLINOIS, A CORPORATION OF ILLINOIS.

CAR-ROOF.

1,112,053.

Specification of Letters Patent. Patented Sept. 29, 1914.

Application filed October 6, 1913. Serial No. 793,578.

To all whom it may concern:

Be it known that I, HENRY A. CHRISTY, a citizen of the United States, residing at the city of Chicago, county of Cook, State of Illinois, have invented certain new and useful Improvements in Car-Roofs, of which the following is a specification.

My invention pertains to the roofs of rail-way-cars, and more particularly concerns improvements in sheet-metal freight car roofs.

One object of the invention is the provision of a roof of this general character which shall be composed of a single thickness of metal, which shall have a frame of adequate strength for all purposes, which will be weather-proof, and the parts of which can be readily assembled and taken apart with facility and dispatch when required to effect repairs.

A further feature of the invention is the prevention of leakage through a car-roof upon which snow or ice are likely to act as a dam, giving rise to the formation of pools of water, which happens not infrequently on account of the slight pitch of car-roofs. To overcome the possibility of leakage through the roof under circumstances of this kind, each permeable joint is provided with a covered drain discharging the water over the eaves, thereby eliminating the possibility of leakage or seepage into the interior of the car.

An additional feature of my improved construction is the avoidance of the employment of rivets through the roof-plates, the use of which is objectionable because of the great difficulty in making the roof structure weather-tight about such fastening-means.

In order that those skilled in this art may have a full and complete understanding of this invention, I have illustrated a preferred embodiment of the same in the accompanying drawings forming a part of this specification and to which reference should be had in connection with the detailed description of the structure.

In the drawings: Figure 1 is a fragmentary side elevation of a car equipped with a roof incorporating this invention; Fig. 2 is a fragmentary vertical section through the roof and a portion of the side-wall; Fig. 3 is another vertical section, the plane of section being at a different point than that shown in Fig. 2; Fig. 4 is a fragmentary en-

larged side-elevation of the roof; Fig. 5 is a horizontal section on line 5—5 of Fig. 3, the parts being viewed in the direction indicated by the arrows; Fig. 6 is a section on line 6—6 of Fig. 2, and, Fig. 7 is a perspective view of one of the roof-plate clips.

In this improved construction the carlines 10 of cambered form and of any desirable shape in cross-section, (in the present instance of inverted channel shape as shown in Fig. 6), extend from side-wall to side-wall of the car and at their opposite ends are fastened to the side-plates 11 by means of suitable brackets 12 which are bolted through the side-plate 11 and the adjacent sheathing 13, and which are also riveted at 14 to the web of the carline. Above the sheathing 13 I employ a Z-bar eave-strip 15 having its inner upstanding flange bearing against the side-plate 11, its horizontal web above the top of the sheathing, and its outer down-turned flange overlapping the top portion of such sheathing, all as is clearly illustrated in Figs. 2 and 3 of the drawings.

Each carline at each end terminates in a flat plate portion or ear 16 disposed just outside of and overlapping the upstanding flange of the eave Z-bar 15. The roof-plates 17 desirably extend from carline to carline and above the carlines the adjoining plates 18 each have an upstanding flange 18, 18, brought directly in contact and held together by means of any desirable number of U-shaped clips 19, 19, fitted over and driven on such flanges, all as is well illustrated in Figs. 2 and 6. These roof-plates extend uninterruptedly from side-wall to side-wall so as to avoid the necessity of providing weather-proof joints along the longitudinal center of the car-roof. These clips or clamps 19 perform an additional function of strengthening the roof longitudinally thereof, it being understood that in a construction of this kind I ordinarily omit the ridge-pole and all purlins, the entire weight of the roof being borne by the carlines proper.

By fastening together these abutting upstanding flanges of the roof-plates by the clips 19, any tendency for the end-walls of the car to become bulged or displaced is resisted by the roof-covering; that is, the metal roof-sheets and their fastening-means. At their outer ends these roof-plates 17, as well as the outstanding flanges 18 are bent down over the ears 16 of the carline and the in-

ner upstanding-flange of the eave-strip 15 so that owing to the pitch of the roof of the rain is readily discharged by these roof-plates over the side of the car, the employment of 5 the eave-strips 15 eliminating all possibility of the water entering the interior of the car at the top of the sheathing.

Over each of the roof-plate joints formed by the abutting roof-plate flanges 18, 18, I 10 employ an inverted channel-shaped cap-strip 20 with lateral flanges 21, 21, on its two sides bearing on the companion roof-plates at opposite sides of the joint, each cap-strip extending from side-wall to side-wall and 15 having its ends 22 downturned over the depending edge-portion of the roof-plates; that is to say, the cap-strips follow and conform to the downwardly-bent joints between adjacent roof-plates. Each cap-strip at the 20 extreme end of its bent portion is flattened to provide an ear or attachment portion 23, which, by means of the bolts 24, 24, is fastened against the outer face of the depending flange of the Z-bar eave-strip 15, such bolts 25 passing through aligned apertures in the various parts and holding the brackets 12 fixedly in position, as is clearly shown in the various figures of the drawing. It should be noted that as is illustrated more in detail 30 in Figs. 5 and 6, these cap-strips are considerably wider than the roof-plate joints which they cover and render weather-proof, that is to say, spaces are provided between the inner faces of the side-walls of the cap-strip and the adjacent faces of the flanges 18 and clamps 19. The purpose of leaving 35 these spaces or cavities is to permit the drainage therein of any water which may enter beneath the flanges 21, that is, between 40 such flanges and the roof-plates, in this manner preventing the possibility of any such water acquiring access to the interior of the car between the contacting flanges 18, 18 of the roof-plates. In order that any such 45 water may be readily discharged at the sides of the car over the eave-strips or bars 15, the the cap-strips are provided with apertures 25 establishing communication between the 50 passages or spaces referred to and the exterior of the car-body side-wall. It should be clear, therefore, that if the drainage of the rain or melting snow or ice from the upper portion of the car-roof is more or less prevented by the presence of snow or ice on 55 the lower or outer portions of the roof, and if any of such water enters beneath the cap-strips, the latter afford ready passages to the sides of the car for the quick discharge of such water, eliminating the possibility of 60 the same entering the car-body through the roof-sheet joints. It should be observed that in this improved construction there are no rivets through any portion of the roof to which water has access and that consequently, there is no danger of leakage about 65

any such rivets. This plan of permitting drainage within the cap-strips and not employing the carlines as troughs is, I believe, broadly new in this art. If for any reason any of these roof-plates become damaged or 70 injured, requiring replacement, this can be readily accomplished by taking off the required number of cap-strips and merely lifting the roof-plates out of place, and substituting for them uninjured ones or repairing 75 the damaged ones. Since the cap-strips are the only means for holding the roof-plates in position the mere un-bolting of such cap-strips and their removal from normal position permits the subsequent lifting of the 80 roof-plates out of place in a quick and easy manner, and their replacement is also expeditiously accomplished.

While the construction herein shown and described is the preferred embodiment of 85 the invention at the present time, it will be understood by those skilled in this art that various minor mechanical changes may be made in such structure without departing from the heart and essence of the invention 90 and without the sacrifice of any of its substantial benefits and advantages. For example; although I have shown the flanges 18 of the roof-plates continuous over the bend at the sides of the car, in some instances 95 it may be preferable to cut such flanges at the bend and insert fillers in the spaces thus provided, securing such fillers in position in any preferred and desirable manner. Such flanges, however, would in effect be continuous, as is desirable in a construction of 100 this kind to assure proper drainage and the avoidance of leakage.

I claim:

1. In a car-roof construction, the combination of car-body side-walls, carlines extending from side-wall to side-wall, sheet-metal roof-plates resting on said carlines and having upstanding marginal flanges along their adjacent edges, the ends of said 110 plates and flanges being bent down over said side-walls to provide efficient drainage over the walls, means fastening said flanges together, and cap-strips fitted over said roof-plate flanges, the side-walls of said cap-strips being spaced away from the upstanding flanges and flange fastening means covered thereby to provide drainage channels within the cap-strips and to permit limited 115 relative movement of the roof-plates and 120 cap-strips, substantially as described.

2. In a car-roof construction, the combination of car-body side-walls, carlines extending from side-wall to side-wall, sheet-metal roof-plates resting on said carlines 125 and having upstanding marginal flanges along their adjacent edges, the ends of said plates and flanges being bent down over said side-walls to provide efficient drainage over the walls, means fastening said flanges to- 130

gether, and cap-strips of inverted channel shape in cross section fitted over said roof-plate flanges, the side-walls of said cap-strips being spaced away from the upstanding flanges and flange fastening means covered thereby to provide drainage channels within the cap-strips and to permit limited relative movement of the roof-plates and cap-strips, said cap-strips having apertured 10 ends down-turned over said side-walls, substantially as described.

3. In a car-roof construction the combination of car-body side-walls, metal eave bars disposed longitudinally of the car-body 15 at the tops of said side-walls, carlines extending from side-wall to side-wall, sheet-metal roof-plates on said carlines and having upstanding marginal flanges along their adjacent edges, the ends of said plates and flanges being bent down over said eave bars

to provide efficient drainage over the side-walls, U-shaped clips fitted over the abutting roof-plate flanges to fasten them together, and cap-strips of inverted channel shape in cross-section fitted over said roof-plate flanges, the side-walls of said cap-strips being spaced away from the upstanding roof-plate flanges and their fastening clips covered thereby to provide drainage channels within the cap-strips, said cap-strips having apertured ends down-turned over the car-body side-walls, substantially as described. 25 30

Signed at Chicago, county of Cook, and State of Illinois, in the presence of the two 35 witnesses subscribed below.

HENRY A. CHRISTY.
